UNITED STATES PATENT OFFICE.

EDMOND W. T. RICHMOND, OF ROMFORD, ENGLAND.

DESIGN FOR A GAS-STOVE.

SPECIFICATION forming part of Design No. 33,884, registered January 8, 1901.

Application filed December 11, 1900. Serial No. 39,564. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the body portion A in the form of double pyramidal frustums having horizontal corrugations, the base B in the form of the frustum

of a pyramid, the lateral projection C, having a flat top and sloping sides, and the cylindrical portions D, projecting upwardly from the top of the body portion. There is also a cylindrical portion E projecting laterally from the body portion.

I claim—

The design for a gas-stove, substantially as herein shown and described.

In testimony whereof I have hereunto subscribed my name.

EDMOND W. T. RICHMOND.
